[57] ABSTRACT

A vehicle having lifting means at its front end to raise a container filled with fruit from the ground to a position for engagement and support by a carriage movable rearwardly over the vehicle. A hopper is normally supported on the vehicle below the carriage which is adapted to dump the filled containers into the hopper, there being means to raise the hopper to an unloading position. The carriage is adapted to stack emptied containers at the rear of the vehicle and to pick up and transfer the stack to another vehicle.

FRUIT CONTAINER PICKUP VEHICLE

BACKGROUND OF THE INVENTION

The present pickup vehicle is designed to pick up containers filled with fruit and previously deposited on the ground, collect the fruit in a hopper on the vehicle, and return the empty containers singly or preferably in a stack to a desired location. Thus, the vehicle can be used to pick up containers of fruit in an orchard regardless of the method of picking. However, the vehicle is particularly adapted to be used in cooperation with a picking apparatus which deposits filled containers in a line between the rows of trees. Such an apparatus is disclosed, for example, in my copending application Ser. No. 14,591, filed Feb. 26, 1970, and entitled Fruit Picking Apparatus and Method.

SUMMARY OF THE INVENTION

It is an object of the invention to provide a novel apparatus for successively picking up filled containers of fruit or other produce, dumping the containers into a hopper carried on said apparatus, and storing the emptied containers.

Another and more specific object is to provide improved carriage and track means cooperating with front lifting means to carry the containers from the lifting means and dump them into a hopper on the vehicle.

A further object is to provide improved support means on the carriage adapted to engage under the containers for supporting, dumping and stacking them when emptied, and for transferring the stack to another vehicle.

A still further object is to provide improved elevating means supporting the hopper for raising it to position for unloading its contents into another vehicle.

These and other objects are attained by the novel and improved parts, assemblies and arrangements comprising the present invention, a preferred embodiment of which is shown herein by way of example, the scope of the invention being defined in the appended claims.

Referring to the drawings:

FIG. 1 is a side elevation, partly broken away, of the improved vehicle.

FIG. 2 is a partial side elevation, showing the improved vehicle being used to deliver a stack of empty containers to a picking apparatus.

FIG. 3 is an enlarged side elevation showing how the empty containers are stacked at the rear of the vehicle.

FIG. 4 is a front end elevation showing the hopper in raised position for unloading produce into a collecting vehicle.

FIG. 5 is a plan view, partly broken away, of the improved vehicle.

FIG. 6 is an enlarged partial side elevation on line 6—6 of FIG. 5, showing the lifting mechanism.

FIG. 7 is a partial sectional view on line 7—7 of FIG. 6.

FIG. 8 is a front elevation on line 8—8 of FIG. 7.

FIG. 9 is a partial section on line 9—9 of FIG. 8.

FIG. 10 is a partial section on line 10—10 of FIG. 8.

FIG. 11 is a plan section on line 11—11 of FIG. 8.

FIG. 12 is a partial section on line 12—12 of FIG. 8.

FIG. 13 is a plan section on line 13—13 of FIG. 8.

FIG. 14 is a plan view, partly broken away, on line 14—14 of FIG. 3.

FIG. 15 is a partial section on line 15—15 of FIG. 14.

FIG. 16 is a cross section on line 16—16 of FIG. 14.

FIG. 17 is a sectional view on line 17—17 of FIG. 14.

FIG. 18 is an enlarged partial section on line 18—18 of FIG. 17.

FIG. 19 is a sectional view on line 19—19 of FIG. 14.

FIG. 20 is an enlarged partial plan view on line 20—20 of FIG. 19.

FIG. 21 is an enlarged elevational view, partly in section, on line 21—21 of FIG. 20.

FIG. 22 is a partial sectional view on line 22—22 of FIG. 21.

FIG. 23 is a similar view showing the gears moved to position the arms in bucket holding position.

FIG. 24 is an enlarged sectional view on line 24—24 of FIG. 20, taken between the gear shafts.

FIG. 25 is a partial section on line 25—25 of FIG. 24.

FIG. 26 is a plan elevation on line 26—26 of FIG. 3, showing the mechanism for raising and lowering the hopper.

FIG. 27 is a side elevation on line 27—27 of FIG. 26, showing the hopper raising mechanism in one position.

FIG. 28 is a similar view showing the hopper raising mechanism in another position.

FIG. 29 is a vertical sectional view of the hopper on line 29—29 of FIG. 27.

FIG. 30 is a partial sectional view through one of the sliding supports for the hopper on line 30—30 of FIG. 27.

FIG. 31 shows the vehicle hopper chute in a discharge position.

DESCRIPTION OF A PREFERRED EMBODIMENT

In FIG. 1, the operation of the improved vehicle is shown somewhat schematically in picking up a filled container or bucket from the ground, carrying it rearwardly over and dumping it into the hopper, and then stacking the empty container at the rear end of the vehicle. In FIG. 2 a stack of empty containers is shown moved to the forward end of the vehicle, for being lowered into stacked position at the rear of a picking apparatus shown in phantom, such as disclosed in my copending application Ser. No. 14,591, filed Feb. 26, 1970.

The improved vehicle has a chassis or frame indicated generally at 10 including stub axles supported on front and rear wheels 11 and 12, a front lifting mechanism 13, an overhead carriage 14 for carrying buckets 15, a central hopper 16, and a rear support ring 17 carried on the hopper by bars 18 for stacking empty containers.

Referring to FIGS. 5—13, the front lifting mechanism preferably comprises laterally spaced upright frame channels 19 supported on a transverse base frame member 20 on the vehicle chassis. The upright channels are connected at their upper ends by transverse bar 21. A pair of inner channels 22 are slidably telescoped within channels 19 and the inner channels are connected together by a transverse bar 23.

The base frame member 20 has a forwardly extending horizontal plate 24 welded thereto which is supported below by gussets 25 welded to member 20. The plate 24 supports the base 26 of a vertical hydraulic cylinder 27 extending upwardly midway of the channels 19. A piston head 28 rests on the upper end of cylinder 27 when the piston is lowered and is slidably upwardly on guide rod 29. Sprockets 30 are journaled in opposite sides of piston head 28 and mesh with chains 31.

The bottom ends of chains 31 are fastened to brackets 32 on transverse plate 33 of a rectangular lifting frame assembly 34 (FIGS. 9 and 10), and bracket plates 35 extend rearwardly of said assembly 34 for journaling rollers 36 which roll on the inner upright channels 22 as the lifting frame is raised and lowered.

The other ends of chains 31 are secured to brackets 41 on cross bar 47 extending between and connected to the outer channels 19. Within the lifting frame are vertical support plates 37 pivoted on cross shaft 38, and brackets 39 at the bottoms of plates 37 are attached to the semicircular lifting fork 40 (FIG. 7), which is adapted to engage under the peripheral channel flange on a circular fruit bucket 15 shown in phantom in FIGS. 5, 6 and 7.

A pair of divergent guide arms 42 extend forwardly from an outer frame 43 surrounding frame assembly 34, and these guide arms serve to straddle the sides of a fruit bucket supported on uneven terrain and have outer upright posts 42' which engage the channel 15' of the bucket to guide the lifting fork 40 into place under the channel without danger of the fork ends scratching or marring the plastic side wall of the bucket. The posts 42' engage and slide along the rim flanges 15' of the bucket until the vertical ribs 34' on frame 34 abut the flanges, at which time the fork is properly positioned to engage under the bottom flange when the fork is raised.

The outer frame 43 includes vertical plates 44 welded at their upper ends to a horizontal plate 45 which extends over the wheel axles 46 and is welded to the chassis 10. The outer frame 43 is hung on the chassis by vertical bars 48 engaging over the plate 45 and attached to base frame member 20 at their lower ends. As shown in FIGS. 9 and 10, the member 20 may have at its upper end a rearwardly and downwardly curved portion supported on a transverse bar 49 extending between and secured to the vertical bars 48.

In the operation of the front lifting mechanism, when fluid pressure is introduced into the lower end of cylinder 27, the piston head 28 carrying sprockets 30 is raised out of the cylinder and the sprockets pull the chains, and with them the lifting frame 34, upwardly, the rollers 36 rolling in the inner channels 22. When the head 28 is raised into abutment with horizontal flange 50 on transverse bar 23 connecting inner channels 22 (FIGS. 8 and 13) the channels are extended upwardly from within channels 19, as indicated in phantom lines in FIG. 8, so that the rollers 36 can raise the lifting frame and a bucket 15 to the position shown in phantom lines in FIG. 6, where the overhead carriage 14 on the vehicle engages the bucket and carries it rearwardly over the hopper 16 therein.

Aside from the lifting fork 40 adapted for engaging under the peripheral channels on the buckets, and the guide arms 42 for said fork, the lifting mechanism just described is substantially conventional and per se forms no part of the present invention.

The carriage 14 is movably supported on spaced-apart channel rails 52 (FIGS. 16 and 17) connected at their front ends on a transverse angle beam 53 resting on a tubular shaft 54 mounted on gusset brackets 55 on the rear sides of the outer upright channels of the front lifting assembly (FIG. 6). The rear ends of the rails 52 are supported on the sides of the hopper 16, and the hopper is supported on an extensible framework for raising it to unloading position shown in FIG. 4, hereinafter described in detail.

The carriage 14 is rollably supported on rails 52 by pairs of longitudinally spaced rollers 60, and the rollers are journaled in angles having one leg 62 overlying the rails and the other leg 63 extending downwardly adjacent the open side of the rails and journaling the rollers. Vertical support plates 64 are welded to and extend upwardly from angle legs 62, and a bridge member 65 extends between and connects the plates 64. As shown in FIGS. 16 and 18, wood strips 66 and 67 are supported above and below the rails for slidably supporting the upper and lower runs 68 and 69 of drive chains. The upper runs of the chains are secured at 61 to the angle legs 62 for moving the carriage. Preferably, horizontal aligning rollers 70 are journaled on the angle legs 63 for abutting the webs of channel rails 52. Sheet metal housing shields 71 and 72 may be provided for the chains and roller assemblies.

Referring to FIGS. 14 and 17, the chains 68,69 are trained around drive sprockets 73 at the rear of rails 52 and around idler sprockets 74 at the front ends thereof. The sprockets 73 are mounted on a transverse shaft 75 having a drive sprocket 76 thereon driven by a pinion 77 on the shaft 78 of drive motor 79.

Referring to FIGS. 15-17, anti-friction bearing assemblies 80 and 81 are supported atop the vertical plates 64, and an inner drive shaft 82 is journaled in said bearings. One end of shaft 82 has a drive sprocket 83 keyed thereto, and a pinion sprocket 84 operatively connected thereto by chain 85 is fixed on shaft 86 of drive motor 87. The shaft 82 has keyed thereon drive sprockets 88 driving chains 89 slidably housed in bucket lifting arms 90 extending forwardly of shaft 82 and meshing with front sprockets 91 in the front ends of the arms. The purpose of the chains 89 will hereinafter be described.

The bucket lifting arms 90 are secured at their inner ends to an outer shaft assembly journaled on the bearings 80 and 81 and rotatable relative thereto. This assembly comprises outer shaft 92 concentric with shaft 82 and secured to the arms 90. Preferably with diagonal brace bars 90' extending between the shaft and medial portions of the arms. The arm adjacent to

drive sprocket 83 is secured by flanged member 93 to one race of bearing assembly 80, and the other arm 90 is secured to one race of bearing assembly 81 by a laterally extending sleeve member 94 on which a drive gear 95 is secured. A drive pinion 96 meshing with gear 95 is driven by motor 97 through gear reducer 98.

Referring to FIGS. 19-25, the outer ends of lifting arms 90 have pairs of clamping arms 100 keyed at their inner adjacent ends on pivot shafts 101 disposed at right angles to the shafts

102 on which the front sprockets 91 are keyed. The shafts 101 are journaled in blocks 103 welded to the inner ends of shafts 102, for combined movement of arms 100 from aligned position shown in full lines in FIG. 20 to an angular position shown in phantom lines where they clamp the peripheral channel of a bucket 15. This movement is controlled by meshing segmental gears 104 fixed on the lower ends of pivot shafts 101, as best shown in FIGS. 22 and 23. A stop bars 105 secured to the inner face of each block 103 limits the opening movement of 20 the clamping arms. The lower ends of the stop bars are preferably inclined to guide the clamping arm assemblies over the bucket rim flanges as the arms are lowered into place for clamping the rim flange to support the bucket.

Channel-shaped shoes 106 are provided on the outer ends 25 of clamping arms 100 for fitting between the flanges of the peripheral channels 15' on the buckets 15 and frictionally abutting the webs of the channels while straddling bolt heads thereon at diametrically opposite points to support a bucket on the carriage.

30 As shown in FIG. 21, the power for operating each pair of arms 100 is supplied by double acting fluid cylinders 107 each pivoted at one end at 108 on one of the arms 100 and pivoted at its other end on a bracket arm 109 projecting outwardly from the block 103 in which the arms are journaled. Rotating one arm 100 will rotate the other arm 100 in the opposite direction due to the meshing gears 104 on the pivot shafts 101 of the arms. As shown in FIG. 24, sprockets 91 are keyed at 112 to shafts 102, and the arms 90 are rotatable on bearings 113 on the shafts.

40 Referring to FIG. 6, when a bucket 15 filled with fruit or produce is raised to the upper position shown by means of the fork 40 (FIG. 7) engaging under the lower flange of peripheral channel 15' on the bucket, the carriage 14 is moved to a forward position on rails 52 with the arms 90 extended forwardly, 45 and the clamping arms are then operated to clamp between the channel flanges on opposite sides of the bucket. The front lifting mechanism is then lowered to pick up and raise another bucket, and the carriage moved rearwardly over the hopper to the phantom position shown in FIG. 3.

50 In this position the bucket is dumped as indicated in phantom in FIG. 1, and then returned to the upright position of FIG. 3 over the hopper, and the arms 90 are then swung upwardly over the carriage 14 to move the bucket while in upright position rearwardly and nest it into the top of a storage stack at the rear of the vehicle. Referring to FIG. 2, the storage stack, or any part thereof, may be picked up and carried forward by the carriage at any desired time, to supply empty buckets to a storage stack on the rear of a picking vehicle, as indicated in phantom lines.

60 In the operation of the carriage while handling the buckets in the foregoing manner, the motor 79 rotates shaft 75 to drive the chains 68,69 and move the carriage back and forth on the rails, as desired. The arms 90 are rotated by operation of motor 97 (FIGS. 14-16) driving the outer shaft 92 on which the arms are secured. Normally the motor 87 is not operated and the inner shaft 82 is thereby held stationary. Thus, as the arms 90 are rotated, the sprockets 88 and 91 therein do not rotate and the chains 89 compensate for the change in angularity of the arms by wrapping around one side of the sprockets and unwrapping from the other side.

65 Since the sprockets 91 are keyed to the shafts 102 the outer ends of arms 90 are rotatable thereon, the shafts 102 maintain the clamping arms 100 and the bucket held therein in a horizontal position as the arms 90 are rotated to various posi-

tions. When bucket is to be dumped into the hopper, the motor 87 is actuated to rotate the inner shaft 82 to tilt the bucket to the position shown in FIG. 1.

In FIGS. 21 and 24, a preferred conduit system is shown for conducting pressure fluid along each lifting arm 90 and to and from the motor 107 which actuates the clamping arms 100 regardless of the relative rotation of the lifting arms 90 and the shafts 102 on which the clamping arms 100 are mounted. As shown in FIG. 24, the outer end of each lifting arm 90 is journaled on bearings 113 for rotating around the shaft 102 and a cover plate 114 over the outer end of shaft 102 is secured by cap screws 115 to a bearing plate 116 welded to the outer face of the end of the arm. The plate 114 has fluid pressure supply ports 117 and 118 extending radially thereof and these ports are connected by conduits 119 and 120 to the supply and exhaust lines (not shown) extending along or through the arm 90.

A circular chamber 121 is provided between the cover plate 114 and the end of shaft 102 and port 117 communicates therewith. A duct 122 extending longitudinally of shaft 102 communicates at its outer end with chamber 121 and at its inner end with a radial port 123 which is connected by a conduit 124 to one of the flexible fluid conduits 125 at the ends of fluid cylinder 107, which serve alternately as supply and exhaust conduits.

The other conduit 125 is connected by conduit 126 to the inner end of another longitudinal duct 127 in shaft 102. At its outer end the duct is connected by radial ports 128 and 129 to an annular slot 130 surrounding the shaft 102 and extending radially outward to intersect the port 118, so that port 127 always communicates with port 118 regardless of relative rotation between cap 114 and shaft 102. The flexible conduits 125 permit the limited swinging movement of cylinder 107 necessary to accommodate the clamping and unclamping movements of arms 100.

The movable support mechanism for raising the hopper 16, together with carriage 14 and track rail assembly, to the unloading position of FIG. 4, is shown in FIGS. 26-30. The supporting framework for the hopper includes outer longitudinal channels 57 and inner longitudinal I beams 134 supporting vertical reinforcing ribs 135 on the hopper and carried on the vehicle frame 10 by a pantographic lever system about to be described.

The main lever arms 136 are pivoted at their front ends to clevises 137 on a transverse member of the frame 10, and their rear ends have yokes 138 pivoted to journal rollers 139 abutting the bottom flanges 140 of beams 134 and having upwardly and inwardly extending retainer flanges 141 slidable thereon (FIGS. 29 and 30). Scissor lever arms 142 are pivoted intermediate their ends to pivot shafts 143 extending through medial portions of main lever arms 136. The front ends of arms 142 are pivoted at 144 to the front ends of the hopper support channels 57, and the rear ends of arms 142 are pivoted at 145 to trailing links 146 pivoted at 147 to the vehicle frame 10.

The power means for operating the lever system to raise the hopper preferably comprises two hydraulic cylinders 148 pivoted at their rear ends at 149 on a transverse member 150 of the vehicle frame, suitably braced by a longitudinal member 151 and diagonal members 152 joined at their front ends to a front transverse frame member 153 (FIG. 26). The cylinders 148 have extensible telescopic pistons in three sections 154a, 154b and 154c, the innermost sections 154c being pivoted at 155 to ears 156 on a transverse bridge member 157 connecting the main support arms 136.

As shown in FIGS. 27 and 28, when the pistons in cylinders 148 are actuated to raise the main lever arms 136, the scissors arms 142 are also raised, and as the rear ends of arms 142 are controlled by links 146 the front ends of arms 142 maintain the hopper support channels 57 and beams 135 substantially

horizontal in parallelism with the vehicle frame members 10. During the raising movement of the lever system, the sliding journals 139 compensate for the arcuate movement of the rear ends 138 of the main lever arms 136 while maintaining the hopper support member substantially horizontal.

As shown in FIGS. 4, 29 and 31, the hopper 16 has a downwardly sloping bottom and a combined gate and discharge chute 160 hinged at 161 to the bottom of one side wall. A downwardly inclined bottom wall portion 162 of the hopper conducts fruit or produce therein to the gate 160 which retains the same when the gate is swung upwardly to the closed position of FIG. 29, and allows it to discharge out of the gate by gravity when swung downwardly to the open position of FIGS. 4 and 31. Hydraulic cylinders 163 pivoted to the hopper on opposite sides of the gate, with their pistons 164 connected to the side walls of the gate, operate the gate to swing it between open and closed position.

Referring to FIG. 4, the height of the hopper in raised position is such that its contents can be discharged into a roadside truck, such as indicated in phantom at 165, of many times the capacity of the hopper 16. In the case of picking oranges, for example, the hopper 16 may collect oranges picked in the grove and dump them into the truck 165 for transport to a juice concentrate plant.

Conventional controls for the various hydraulic motors previously described, as well as for the various hydraulic cylinders, are located conveniently within reach of an operator seated in the driver's seat 167 of the vehicle, so that from his seat he can control the operations of bringing the front of the vehicle up to a filled container on the ground, lifting, dumping and stacking the containers, returning a stack of empty containers to a picking vehicle, and raising and unloading the hopper.

Accordingly, a novel and improved apparatus has been disclosed and described herein for carrying out the foregoing operations in an efficient manner.

I claim:

1. A pick-up vehicle for lifting and dumping filled produce containers and temporarily storing the unloaded empty containers, comprising a hopper carried on the vehicle, means on said vehicle in front of said hopper for engaging and lifting filled containers successively from the ground, a track on the hopper, carriage means on said track for moving each container over said hopper, vertically rotatable lifting arms on said carriage means for receiving a container from the lifting means, carrying the container to dumping position, dumping said container into said hopper and stacking the emptied containers, and means for unloading said hopper.

2. A vehicle as defined in claim 1, in which the carriage means has means for maintaining the container in upright position as the arms are rotated.

3. A vehicle as defined in claim 2, in which the carriage means has independent means for tilting the container while supported in the lifting arms.

4. A vehicle as defined in claim 1, in which the carriage means has means for tilting the container while supported in the lifting arms.

5. A vehicle as defined in claim 1, in which the lifting arms have horizontally rotatable clamping arms at their outer ends, means to rotate the lifting arms, and separate means to rotate the clamping arms to grip a container between the lifting arms.

6. A vehicle as defined in claim 5, in which the carriage means has means for maintaining the container in upright position as the pick-up arms are rotated.

7. A vehicle as defined in claim 5, in which the carriage means has means for tilting the container while supported in the lifting arms.

8. A vehicle as defined in claim 6, in which the carriage means has independent means for tilting the container while supported in the clamping arms.
